UNITED STATES PATENT OFFICE.

WILLIAM C. PARSONS, OF PENNINGTON GAP, VIRGINIA.

HORSE-DETACHING DEVICE.

SPECIFICATION forming part of Letters Patent No. 680,351, dated August 13, 1901.

Application filed December 28, 1900. Serial No. 41,406. (No model.)

To all whom it may concern:

Be it known that I, WILLIAM C. PARSONS, a citizen of the United States, residing at Pennington Gap, in the county of Lee and State 5 of Virginia, have invented certain new and useful Improvements in Horse-Detaching Devices; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 This invention relates to new and useful improvements in detaching devices for harnesses, whereby when a team becomes unruly it may be readily detached from the vehicle, thus avoiding possible injuries to life and 20 limb in runaways, &c.

More specifically, the invention consists in the provision of means for disconnecting a 25 hame-fastening strap and a trace from a rod carried by the hame automatically with the disconnecting of the driving and check reins from straps fastened to the bridle.

To these ends and to such others as the invention may pertain, the same consists, further, in the novel construction, combination, 30 and adaptation of parts, as will be hereinafter more fully described and then specifically defined in the appended claims.

The invention is clearly illustrated in the accompanying drawings, which, with the letters of reference marked thereon, form a part 35 of this application, and in which drawings—

Figure 1 is a view showing my improved detaching device as applied to a harness. Fig. 2 is a detail view showing the manner of holding the trace to the hame. Fig. 3 is a side elevation of the mechanism shown in Fig. 2. Fig. 4 is a view showing the check-detaching device, and Fig. 5 is an edge elevation of the check-releasing device. Fig. 6 is a detail view 45 of the ends of the belly-band straps and retaining-strap held in slits therein.

Reference now being had to the details of the drawings by letter, A designates a pair of traces of a double harness, and B one of 50 said hames, having a strap B², which is bent over the end of the hame B and secured thereto and has a projecting portion b, which is

apertured to receive the hooked end C² of the bar C. Said bar C has a loop or buckle C³ pivoted near its hooked end, through which a 55 strap may pass to secure said buckle to the loop or buckle mounted on the end of a second hame. (Not shown.) Said strap B² has guide-pieces C⁴ at one of its ends on the outer edge of the hame B for the purpose of holding the shank portion of the bar C when the latter is held in a locked relation or in a position to fasten the ends of the hames to the collar C⁵, which is of ordinary construction. Said bar C is bent into a compound curve at 60 a location slightly above said guide-pieces on the strap B², so as to conform to the contour of the hame and to contact with the front face of the hame B, and is then bent at right angles, forming a hook C⁶ at its free upper end, over 65 which a ring E is adapted to engage, and through which ring E a neck-yoke chain F is adapted to pass. Secured to the outer face of the hame B is a staple M, and hung on said staple is a ring M', which is adapted to engage 70 over the upper end of the bar C in order to hold the latter against the hame B and retain the ring E on the hooked end of the bar C. Fastened to the ring M' is a cord M², which after passing through a screw-eye M³ on the 75 hame B extends rearward and is fastened to the operating-lever n, which is pivoted to the wagon-box at any convenient location. The traces A are secured at their forward ends to hooks A', which are fastened by means 80 of staples to the hames of the harness. In Fig. 1 of the drawings only one of said traces is shown; but there are of course four of these traces in a double harness similarly mounted 85 and connected as described.

The bridle of my harness is of ordinary construction and has reins J detachably connected to the bit-rings, and a check-strap N, which is fastened to a hook N² on the saddle 90 of the harness, passes through guide-loops on the throat-strap of the bridle and connected also to the bit-rings and is provided with detachable means, which will be hereinafter 95 fully described.

The mechanism for detaching the reins and the check-strap from the bridle consists of a buckle O, having cross-pieces O' and a tongue P, which is formed by bending a wire upon itself to receive the hook T, which is formed 100

out of the wire forming the buckle O, said hook T being slightly wider than the space between the portions of wire forming the tongue and adapted when in a locked relation 5 to spring over said hook to hold the tongue normally against the outer face of the buckle O. Projecting from the inner portions of said tongue are lugs Q, which engage apertures R in the checkrein. The check-strap 10 is provided with two of these detaching-buckles, and each driving-rein is provided with one similarly constructed. The check-strap is composed of three sections, one of which is secured at its ends to the buckles O 15 and one on each side of the bridle, which are fastened to the bit-rings in any suitable manner. To an eye X at the end of each tongue P is secured a cord X', the other end of which is fastened to the trace, or, if preferred, the lower end of said cord may be attached to the detachable hame, whereby as the operator pulls upon the cord M² to release the ring from the upper end of the hame-retaining bar the cords X', when the trace pulls 20 backward, will cause the free end of each tongue P to become detached from the hook T and allow the check-strap to become disconnected. At any convenient location in each rein a similarly-constructed buckle with 25 hinged tongue is provided, and each tongue has connection either with the traces or one of the hames, whereby as the hames become detached from the collar the reins, as well as the check-strap, will be automatically detached from the portions of the reins which are connected to the bit-rings.

The belly-band I, instead of having a buckle for connecting its two ends, has its ends slit, as at I', and a locking key or strap I² is 40 passed through said slits, and the forward end of the strap I² is connected to the collar of the harness at a location adjacent to the connecting-strap which fastens the lower ends of the hames. By this provision of means for disconnecting the belly-band it will be noted that when the traces and the hames are disconnected from the harness the locking strap or key being held to the collar will draw through 45 said slits and allow the two slitted ends to become disconnected.

From the foregoing it will be observed that when the operator throws the lever n rearward the hames and traces, as well as the check-strap and driving-reins, will become 55 detached, respectively, from the collar and the bridle, and the entire harness, with the exception of the collar and the bridle, is disconnected from the horse.

Having thus described my invention, what I claim to be new, and desire to secure by Letters Patent, is—

1. In a horse-detaching apparatus, the combination with the hames, traces secured thereto, a rod having a hooked end detachably held to one of the hames and connections between said rod and the second hame, means for holding said rod to the hame and

means for releasing the upper end of the rod when it is desired to disconnect the hames, as set forth.

2. A horse-detaching device, comprising the hames, a rod having a hooked end engaging one of the hames, and connections between said rod and the second hame, a ring carried by said rod and adapted to hold the neck-yoke chain, means carried by the hame to engage and hold said rod to the hame, and connections for disengaging the rod to allow the neck-yoke chain and the hames to be disconnected, as set forth.

3. In a horse-detaching device, a hame, a socket member secured thereto, a rod having a hooked end engaging said socket, a hame-strap secured to said rod, guide-pieces integral with said socket member for holding 85 said rod against lateral movement, the upper end of the rod being bent to form a hook, a neck-yoke-chain ring carried by said hook, and means carried by the hame to engage said hook and hold the same to the hame, 90 and cord connections for releasing the rod from the hame, as set forth.

4. In a horse-detaching device, the combination with the hame, a plate with a socket portion and integral guide-pieces, a rod having a hook to engage said socket, a hame-strap secured to said rod, said rod adapted to be held against lateral movement between said guide-pieces, the upper portion of the rod being bent to one side, and a hook formed 100 at its end, a neck-yoke-chain ring engaging said hook, a staple secured to the hame and a loop or ring retained thereby, adapted to fit over the hooked end of said rod, a rope secured to said loop or ring, whereby as said 105 ring to which the cord is connected is raised over the end of said rod, the latter is allowed to fall by gravity and the hame to become detached, as well as the neck-yoke-chain ring, 110 as set forth.

5. In a horse-detaching device, the combination with a hame, and means for connecting same to a second hame, a cord for detaching said hames, traces held to the hames, the check and driving reins, connections between said reins and the traces, whereby as the hames are disconnected, said reins will become detached, as set forth.

6. In a horse-detaching device, a hame and connections for detaching the same and a 120 cord for releasing the same, a trace secured to said hame, the check and driving reins each having a buckle with tongue designed to be detachably held to said buckle, connections between the tongue or each buckle and a trace, whereby as the hames are released, said cord connected to the traces will cause the tongues of said buckles to swing outward and release the check and driving reins, as set forth.

7. In a horse-detaching device, the combination with a hame, means for disconnecting same, a trace secured to said hame, the check and driving reins, each rein having a buckle to which one end of the rein is secured, said

buckle having a tongue with lugs thereon adapted to be held in a locked relation over an integral hooked portion of the buckle, a bit-engaging strap having apertures which are engaged by said lugs and held to the buckle, and cord connections between said tongue and the trace, whereby as the hame is disconnected the tongue will be opened and the rein released from the bit-engaging strap as set forth.

8. In combination with the hame, a trace, the collar on which the hame is mounted, the check and driving reins, connections between

same and the trace for detaching said reins, the girth having slits therein and a strap secured at one end to the collar and passed through the registering slits in said girth, whereby as the harness is detached and drawn rearward, the ends of said girth will become detached, as set forth.

In testimony whereof I affix my signature in presence of two witnesses.

WILLIAM C. PARSONS.
